UNITED STATES PATENT OFFICE.

BENJIMAN HEEREN, OF MINNEAPOLIS, MINNESOTA.

SNUFF-BOX OPENER.

1,381,831.

Specification of Letters Patent. Patented June 14, 1921.

Application filed March 31, 1920. Serial No. 370,069.

To all whom it may concern:

Be it known that I, BENJIMAN HEEREN, a citizen of the United States, residing at Minneapolis, in the county of Hennepin and 5 State of Minnesota, have invented certain new and useful Improvements in Snuff-Box Openers; and I do hereby declare the following to be a full, clear, and exact description of the invention, such as will enable others 10 skilled in the art to which it appertains to make and use the same.

My invention has for its object to provide an extremely simple and efficient device for opening snuff boxes or other boxes or cans 15 which have detachable covers and paper wrappers; and to such ends, generally stated, the invention consists of the novel construction and combination of parts hereinafter described and defined in the claim.

20 Snuff boxes and various other cans, as is well known, have flanged covers telescoped with the body of the can or box and usually have paper wrappers stuck to the exterior of the box and to the flange of the cover, and 25 normally holding the covers in working position. To open the box or can by the removal of the cover, it is then necessary to break or cut the paper wrapper on the line of the lower edge of the flange of the cover; 30 and it is the object of my invention to provide a very cheap and simple attachment to the cover, by the use of which, this cover and the wrapper may be quickly and easily opened.

35 The invention is illustrated in the accompanying drawings wherein like characters indicate like parts throughout the several views.

Referring to the drawings:

40 Figure 1 is a perspective view showing a snuff box with my opener or wrapper cutter applied thereto and illustrating the manner in which the device is adapted to be used;

45 Fig. 2 is a fragmentary perspective showing a portion of the snuff box and the cutter applied thereto.

The numeral 3 indicates the body of the snuff box and the numeral 2 the cover there- 50 of. The box 3 may be assumed to be stamped from heavy paper or paste board, while the cover 2 will usually be of metal. The numeral 4 indicates the paper wrapper which will be stuck to the exterior of the box 55 and to the outer surface of the flange of the cover 2 in the customary way.

The cutter is formed from a single piece of thin sheet metal, preferably bent to form a top plate 5 having at one end a U-shaped depending cutter blade 6. The top plate 5 60 is adapted to lie flatwise upon the top of the cover 2 and the U-shaped cutter blade 6 embraces the depending flange of the cover, thus interlocking the cutter to the flange of the cover and to the top thereof. 65 Otherwise stated, the cutter is interlocked to the cover with freedom for traveling movements along the depending flange thereof. Of course, the outer part of the blade 6 is on the exterior of the flange of 70 the cover and the inner portion of said blade is between said flange and the upper portion of the box 3. To facilitate movement of the cutter, the top plate 5 is provided with a flange 6 that will be normally turned 75 down against the said plate, as indicated by dotted lines in Fig. 2, but is adapted to be turned upward, as shown in Figs. 1 and 2, to afford a finger piece which, when engaged by the finger and thumb, adapts the 80 cutter to be moved along the flange of the cover with the plate 5 traveling on the top of the cover.

This cutter will be applied to the cover before the cover is applied to the box or 85 can and, thereafter, the wrapper or paper cover 4 will be applied to the box and to the flange of the cover and around the blade 6. When the cutter is moved from its initial position, it will break through the wrap- 90 per and, thereafter, sliding movement there- 95 of along the flange of the cover will cause the wrapper to be cut or severed along the lower edge of the cover flange, to wit, along the dotted line marked y—y on Fig. 1, and this, as is evident, will free the cover for re- 100 moval from the box, and moreover, will loosen the flange from the upper portion of the box. After the cover has thus been loosened and freed for removal, the flange 105 6 can be turned back or downward against the plate 5, so that it will be out of the way, and in fact, the entire cutter, while not re- moved from the cover, will be entirely out of the way and permit the box to be there- 110 after used, just as if the cutter had dis- appeared.

Obviously, this cutter can be applied to snuff boxes and cans at a very trifling cost.

What I claim is:

The combination with a box or can and a flanged cover therefor, of a cutter slidably

interlocked to the flange of said cover and adapted to be moved thereon, the said box or can having a paper wrapper that is normally stuck to the body thereof and to the 5 rim of said cover, the said cutter comprising a U-shaped blade that embraces the flange of said cover and a body plate that

rests on the top of said cover, the said body portion having a flange adapted to be bent down against the same or to be turned up- 10 ward for use.

In testimony whereof I affix my signature.

BENJIMAN HEEREN
